UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

RAIL JOINT WITH LIGHTENED WEB.

Application filed July 9, 1923. Serial No. 650,452.

To all whom it may concern:

Be it known that I, BENJAMIN WOLHAUPTER, citizen of the United States, residing at New Rochelle, in the county of Westchester and State of New York, have invented certain new and useful Improvements in Rail Joints with Lightened Webs, of which the following is a specification.

This invention relates to rail joints and has for its primary object the provision of a joint bar provided with a web portion containing a minimum quantity of metal and yet possessing adequate strength and stiffness for carrying the loading strains and stresses from the head to the foot portion of the bar.

To that end the invention contemplates a novel and practical distribution of metal in the web of the bar so as to leave trussing ribs and intervening pockets or depressions in the bar thereby to permit the metal to be distributed so as to save a substantial amount thereof and thus reduce the cost and weight of the bar.

A further object of the invention is to provide a joint bar with a lightened web and having inclined trussing members which are an integral part of the web and may be formed during the process of rolling the bar thereby avoiding the necessity of afterwards strengthening or stiffening the web of the bar by supplemental means.

With the above and other objects in view which will more readily appear as the nature of the invention is better understood the same consists in the novel construction, combination, and arrangement of parts, hereinafter more fully described, illustrated and claimed.

A preferred and practical embodiment of the invention is shown in the accompanying drawings, in which:—

Figure 1 is a perspective view illustrating one of the forms of my invention.

Figure 2 is a vertical sectional view taken on the line 2—2 of Figure 1.

Figure 3 is a horizontal sectional view taken on the line 3—3 of Figure 1.

Figure 4 is a detail perspective view of a modification of the invention.

Figures 5 and 6 are respective vertical and horizontal sectional views taken on the line 5—5 and 6—6 of Figure 4.

Figure 7 is a detail perspective view of a further modification.

Figures 8 and 9 are respectively vertical and horizontal sections taken on the line 8—8 and 9—9 of Figure 7.

Figure 10 is a further modification of the type of web shown in Figure 7.

Similar reference characters designate corresponding parts throughout the several figures of the drawings.

The present invention aims to produce a joint bar of the character set forth by the rolling method, the limitations of which have heretofore made it very difficult to obtain a bar effecting a maximum economy of metal which would render the bar comparatively light and yet of adequate strength to withstand the loading strains imposed on the joint in track.

The present bar herein proposed has taken into consideration the limitations of the rolling method and observes requirements of standard rolling mill practice and provides a novel web construction which permits of a maximum economy of metal in the portion of the bar where the compression and tension forces tend to neutralize about the horizontal neutral axis of the bar.

Accordingly, the present invention contemplates the provision of a rolled joint bar having a lightened web including integral inclined trussing ribs produced by sub-normal displacements of metal, and although the invention may be carried into effect in connection with joint bars of various types, by way of illustrating the range of embodiment of the invention, reference may first be made to Figures 1 to 3 of the drawings wherein the joint bar A of substantially I-bar formation is provided with the web portion B connecting the head C and foot D. The said web portion B has the inner face thereof formed with the oppositely inclining trussing ribs 1 defining therebetween substantially triangular pockets or depression 2 which extend partly through the thickness of the web and represent metal saved in the finished bar. This arrangement produces a novel trussing construction at the inner face of the bar and yet adequately provides for carrying the loading strains and stresses through the bar as well as permitting the wave motion to easily pass through the joint.

According to the embodiment shown in Figures 4, 5 and 6, the web B is provided with a plurality of pockets 3 opening at op-

posite faces of the bar and grouped in such a way as to leave unbroken inclined trussing areas 4 extending from the head to the foot of the bar. The said pockets or depressions 3 are preferably of such a depth as to leave an undisturbed web portion 5 connecting the head and foot of the bar thus preserving the desirable I-bar formation and yet providing a relatively thin continuous web 10 portion 5 which has the benefit of the reinforcing effect of the trussing reinforcing areas 4 and the additional advantage of being light due to the removal of the metal to form the pockets or cups 3.

15 Another modification is shown in Figures 7, 8 and 9 of the drawings wherein the idea of integral inclined trussing ribs is further carried forward, the web of the bar being formed with diagonal grooves 6 and intervening diagonal braces 7. As illustrated in this form of the invention the inclined diagonal braces 7 and the intervening grooves 6 may be formed on both sides of the bar and in that event the grooves and braces are inclined in opposite directions thus producing a double lattice of diagonal braces. In Figure 10 there is disclosed a modification of the invention wherein the diagonal braces 7^a are formed only at one side of the bar 25 while the outer face 8 is made plain or flat.

From the foregoing it will be seen that the present invention aims to provide a joint bar having a lightened web which may be formed by making sub-normal depressions 35 at one or both sides of the web and using the depressions in such a way as to leave the web reinforced by a series of integral diagonal braces forming a lattice truss. As shown in Figure 1 of the drawings the web 40 is lightened by a series of triangular depressions 2, while in Figure 4 the web is lightened by making a series of circular pockets or sockets which lie wholly within planes defining the inner and outer face of 45 the web and are so spaced that the material between them will form a diagonal lattice construction to reinforce the bar.

It will of course be understood that the bars may be provided with the usual bolt holes H at desirable and convenient locations.

Without further description it is thought

that the many features and advantages of the present invention will be readily apparent and it will of course be understood 55 that changes in the form, proportion and minor details of construction may be resorted to without departing from the spirit of the invention or scope of the appended claims.

I claim:—

1. A rolled rail joint bar including a web having sub-normal displacements of metal producing inclined trussing ribs extending from the head to the foot of the bar. 65
2. A rolled rail joint bar including a web having sub-normal displacements of metal producing integral inclined trussing ribs extending from the head to the foot of the bar. 70
3. A rolled rail joint bar including a web having sub-normal displacements of metal producing integral stiffening members arranged in lattice truss formation. 75
4. A rolled rail joint bar including a web having sub-normal displacements of metal producing integral inclined stiffening members arranged in lattice truss formation. 80
5. A rolled rail joint bar including a web having sub-normal displacements of metal producing integral trussing ribs arranged in lattice truss formation and extending from the head to the foot of the bar. 85
6. A rolled rail joint bar including a web having sub-normal triangular recesses respectively adjacent the head and foot of the bar and producing integral inclined stiffening truss members. 90
7. A rolled rail joint bar including a web having a face reduced by sub-normal depressions forming a plurality of inclined stiffening ribs. 95
8. A rolled rail joint bar including a web having sub-normal displacements of metal in one face thereof and arranged at intervals to provide inclined stiffening ribs between the depressions.

In testimony whereof I hereunto affix my signature in the presence of two witnesses.

BENJAMIN WOLHAUPTER.
